UNITED STATES PATENT OFFICE.

LEONARD H. DES ISLES, OF CHICAGO, ILLINOIS.

FASTENER FOR RAILWAY-RAILS.

1,006,468.

Specification of Letters Patent. Patented Oct. 24, 1911.

Application filed January 9, 1911. Serial No. 601,659.

To all whom it may concern:

Be it known that I, LEONARD H. DES ISLES, a citizen of the United States, and a resident of Chicago, county of Cook, and State of Illinois, have invented certain new and useful Improvements in Fasteners for Railway-Rails, of which the following is a full, clear, and exact description.

The invention relates to rail fasteners and seeks to provide a simple and effective construction which can be securely interlocked with the wooden tie to secure the rail thereto, and which can be effectively employed to replace spikes which have become loosened because of the enlargement of the spike holes caused by the wearing or rotting away of the wood about the spike.

The invention consists in the features of improvement hereinafter set forth, illustrated in the preferred form in the accompanying drawing and more particularly pointed out in the appended claims.

In the drawing, Figure 1 is a view illustrating the spike of the improved fastener in elevation and showing the sleeve portion thereof and portions of the tie and rail base in section. In this view the parts are shown in the position assumed before the spike is driven. Fig. 2 is a similar view showing the parts in the position assumed when the spike is driven home. Fig. 3 is a view of the lower end of the fastener. Fig. 4 is a cross section on the line 4—4 of Fig. 1. Fig. 5 is a plan view with parts shown in section 35 on the line 5—5 of Fig. 2.

The drawing illustrates portions of the wooden tie 6 and of the rail base 7 resting thereon. The improved fastener comprises a sleeve 8 which is preferably cylindrical in form and is adapted to be inserted in a hole bored in the tie, adjacent the base of the rail. The bore of the sleeve extends throughout the greater portion of its length, but its lower end is closed and is preferably flat, so that it will firmly seat upon the bottom of the hole formed in the tie. The solid bottom portion of the sleeve is formed into an upwardly facing wedge 9 having slightly curved, concave side faces. The walls of the sleeve opposite the faces of the wedge 9 are cut away to form openings 10, so that the wedge is connected to the sleeve by portions 11. At its upper end the sleeve 8 is provided with a supporting flange 12 which is adapted to rest upon the upper face of

the tie. This flange is preferably cut away on one side at 13 to clear the base of the rail and permit the insertion of the sleeve into the tie at a point closely adjacent the base of the rail. This cut-away portion of the flange also serves to properly position the sleeve and wedge 9 thereof with reference to the rail base.

The sleeve is expandable and for this purpose is provided with a number of longitudinal slots 14 extending throughout the greater portion of the length of the sleeve and through the flange 12 at its upper end. In the form shown, there are two of these slots, but it will be understood that more may be provided if desired. These slots preferably terminate short of the openings 10 so that bridge portions 15 are left which extend across the upper edges of the openings 10 and the lower edges of these portions are preferably square, as shown, and are located slightly above the edge of the wedge 9.

The spike 16 is adapted to be driven into the sleeve 8 to expand the same. It is preferably of general cylindrical form, as shown, but tapers from its upper headed end to its lower end. At its upper end, the spike is provided with a suitable driving head 17 having a portion adapted to overlap and bear upon the base flange 7 of the rail. Beneath the head, the spike is provided on one side with an abutment 18 which, when the spike is driven home, is adapted to snugly engage the edge of the rail base 7. The upper portion of the sleeve is provided with a notch 19 to receive the abutment 18 on the spike. The lower end of the spike is split to form portions or members 20 having separated lower ends or lips 21 which are adapted to engage the faces of the wedge 9, so that the members 20 will be deflected in opposite directions through the openings 10 of the sleeve and into the wooden body of the tie as the spike is driven.

In applying the fastening device, a hole of proper depth is formed in the tie adjacent the base flange and the sleeve is placed therein with its lower end upon the bottom of the hole and with the flange 12 at its upper end arranged to engage the upper face of the tie. The bolt is then inserted, as shown in Fig. 1. As stated, this bolt tapers from its head end to its lower end and it is of such size that its mid-portion will snugly

fit within the upper end of the sleeve, as indicated in Fig. 1. Then, as the spike is driven home to the position shown in Fig. 2, it will expand the split sleeve 8 and force the portions thereof outwardly into firm binding contact with the wooden body of the tie. At the same time the engagement of the wedge 9 with the split lower end of the bolt will deflect the portions 20 thereof 5 in opposite directions so that the latter are bent into curved form and forced outwardly through the holes 10 into the body of the tie. The inner faces of the separated lips 21, which first contact with the faces of the wedge 9, are outwardly inclined and preferably curved and the metal on the outer faces of the lips is cut away or reduced so that the lips are relatively thin. This arrangement insures that the lips 21 will start in such a 10 proper direction that, when the spike is driven home, the members 20 will be outwardly and upwardly curved as shown in Fig. 2 to effectually clench the spike into the tie. The flat lower end of the sleeve and 15 the flange 12 at its upper end assist in holding the sleeve in position as the spike is driven, and the wedge 9 is thus held in position to properly expand or deflect the portions 20 of the lower split end of the spike. 20 The portions 15 of the sleeve are so disposed 25 with reference to the wedge 9 that their lower edges will engage the outer faces of the spike members 20 and coöperate with the wedge to bend them into proper clenching 30 curve form. Moreover, the deflected portions 20 of the spike will bind between the lower square edges of these portions and the faces of the wedge 9 so that the spike cannot be readily withdrawn. To assist this 35 binding action, the side portions of the spike 40 which engage these edges when the spike is driven home, are preferably provided with a series of beveled teeth 22 which are arranged to pass over the lower edges of the 45 portions 15 as the spike is driven, but engage the same and resist the withdrawal of the spike from the sleeve.

The spike is firmly gripped by the sleeve as it is driven into the sleeve to expand the 50 same. The deflected portions 20 of the spike and the walls of the sleeve 8 engage the tie to securely hold the fastening device in position with the head 17 and abutment 18 of the spike engaging the upper and edge faces 55 of the base flange 7 of the rail. The sleeve 8 is of considerable size and has, therefore, a comparatively large area which, as the spike is driven into the sleeve to expand it, is forced with considerable pressure into firm 60 binding contact with the body of the tie. As the sleeve is larger than the ordinary spike, the improved fastener can be advantageously employed to replace loose spikes where the spike holes have become enlarged. 65 Moreover, the sleeve affords a bearing of

large area for the fastening device in the tie and enables it to more readily resist the thrust and pounding of the rail thereon.

It is obvious that changes could be made in the details set forth without departure 70 from the essentials of the invention, as defined in the claims.

I claim as my invention:—

1. A rail fastener comprising an expandible split sleeve and a split spike adapted to 75 be driven into said split sleeve to expand the same, said spike having a driving head arranged to overlap the base of the rail, and said sleeve having openings in the side walls and means for deflecting the members of 80 said spike outwardly and upwardly through said openings into clenching curve form, substantially as described.

2. A rail fastener comprising an expandible sleeve and a split spike adapted to be 85 driven into said sleeve to expand the same, said spike having a driving head arranged to overlap the base of the rail, and said sleeve having a supporting flange at its upper end, openings in its walls at its lower end 90 and a wedge between said openings for deflecting the members of said spike in opposite directions through said openings, substantially as described.

3. A rail fastener comprising a split ex- 95 pansible sleeve adapted to be inserted in the tie adjacent the rail base and a tapered split spike adapted to be driven into said sleeve to expand the same, said spike having a driving head arranged to overlap the rail 10 base, and said sleeve having openings in its walls and a wedge between openings arranged to deflect the members of said spike outwardly through said openings, substantially as described.

4. A rail fastener comprising a split ex- 10 pansible sleeve having a supporting flange at its upper end, a tapered, split spike adapted to be driven into said sleeve to expand the same, said spike having a driving head arranged to overlap the rail base, the members of said spike having outwardly flaring tapered lower ends, and said sleeve having openings at its lower end with a wedge between said openings for engaging the inner faces of said openings and portions above said openings and adjacent said edge for engaging and binding on the outer faces of said spike members, whereby said spike members are bent outwardly and upwardly 1 into clenching curve form as the spike is driven, substantially as described.

5. A rail fastener comprising a sleeve adapted to be inserted in the tie adjacent the rail base, a split spike adapted to be driven into said sleeve and having a driving head arranged to overlap the rail base, the members of said spike having outwardly flaring, tapered lower ends, and said sleeve having openings in its walls at its lower end

with a wedge between said openings for engaging the inner faces of said spike member and portions above said openings having edges arranged to engage and bind upon the outer faces of said spike members, substantially as described.

6. A rail fastener comprising an expandible sleeve, and a split spike adapted to be driven into said sleeve to expand the same, 10 said spike having a driving head arranged to overlap the rail base and an abutment beneath said head for engaging the edge of the rail base, said sleeve having a wedge at its lower end with openings in its walls on opposite sides of said wedge through which the members of said spike are oppositely deflected by said wedge, substantially as described.

7. A rail fastener comprising a sleeve, a 20 split spike adapted to be driven into said sleeve and having a driving head arranged to overlap the rail base, said sleeve having

a wedge between side openings therein arranged to deflect the members of the split spike through said openings, and said spike 25 having teeth on its outer face arranged to interlock with the edges of said openings, substantially as described.

8. A rail fastener comprising a cylindrical split sleeve having a supporting flange at its upper end, a tapered spike adapted to be driven within said sleeve to expand the same, said spike having a driving head arranged to overlap the rail base, said sleeve having side openings with a deflecting wedge 30 between said openings to engage the inner faces of the members of said split spike and portions above said openings to engage the outer faces of said spike members, substantially as described.
